United States Patent Office

Des. 204,155
Patented Mar. 22, 1966

204,155

CIGARETTE-LIGHTER OR SIMILAR ARTICLE

Robert Hocq, 28 Ave. Marceau, Paris 8, France

Filed June 17, 1964, Ser. No. 80,439

Claims priority, application France Dec. 24, 1963

Term of patent 14 years

(Cl. D48—27)

FIG. 1 is a perspective front-view of the cigarette-lighter or similar article in closed condition.

FIG. 2 is a similar perspective front view showing the ornamental casing of the lighter with the cover removed. The rear view of the lighter of FIG. 2 is identical with the front view.

FIG. 3 is a plan view from above.

I claim:

The ornamental design for a cigarette-lighter or similar article as shown and described.
